UNITED STATES PATENT OFFICE.

THOMAS W. ALLEN, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA.

GARNETT MACHINE.

Application filed January 19, 1927. Serial No. 162,163.

One object of my invention is to so arrange the teeth of the cylinders of a Garnett machine that coarse fibrous woven material can be readily reduced to fibres.

5 Heretofore, it has been difficult to separate the fibres of the warps or wefts of the fabric when the threads extended parallel with the teeth, as the longitudinal threads are removed from the fabric and pass into the 10 space between the teeth without being acted upon by the teeth.

By my invention, all threads of the fabric are separated in the fibres.

A further object of the invention is to provide 15 means for holding the toothed cylinders in alignment.

In the accompanying drawings:

Fig. 1 is a diagrammatic side view of a Garnett machine to which my invention is 20 applied;

Fig. 2 is an enlarged side view showing a stripper and two workers;

Fig. 3 is a sectional view on the line 3—3, 25 Fig. 2, showing the teeth and the bearings only in section;

Fig. 4 is an enlarged view showing the relation of the teeth of two cylinders;

Fig. 5 is a sectional view on the line 5—5, 30 Fig. 4; and

Fig. 6 is a perspective view showing two tooth-strips mounted on a cylinder.

Referring to the drawings, 1 is the main cylinder, 2 are the strippers, and 3 are the workers of a Garnett machine. The other 35 cylinders are common to this type of machine.

In the enlarged views 2 and 3 are shown the stripper and worker cylinders 2 and 3, mounted respectively upon shafts 4 and 5, 40 adapted to suitable bearings.

On the end of the shaft 4 is a gear-wheel 6 which meshes with gear-wheels 7 on the shafts 5, all three gear-wheels being of the same diameter in the present instance. The gear-wheel 6 is flanged as at 8 and the flanges overlap the gear-wheels 7—7, keeping all three gear-wheels and their cylinders in longitudinal alignment.

50 In the present instance, the gear-wheel 6 is made separate from the disks which form the flanges 8, while the flange-forming disks are secured to the gear-wheel 6 by bolts 9.

Referring to Figs. 4 and 5, 2 is the stripper cylinder, and 3 is one of the worker cylinders. Each cylinder has a spiral groove 55 10 cut therein, and the convolutions of the grooves are a given distance apart. Mounted in the groove of the stripper cylinder 2 is a toothed strip 11. The teeth 12 of the strip are long and tapered as shown in the 60 drawings, and are thicker at the base than at the point. The base 13 of the strip is wider than the teeth, the teeth being set to one side of the strip so as to leave a shoulder 14. In the present instance, one side of 65 each tooth 12 is at right angles to the base of the tooth, while the other side is tapered from the shoulder 14 to the point.

The long teeth 12 of the stripper extend within the peripheral line of the teeth of 70 the worker, as clearly shown in Fig. 5, but are spaced therefrom as shown in the same figure.

It will be noticed that the base of the tooth-strip is of a greater thickness than 75 the depth of the groove 10, so that the shoulder 14 is some distance from the face of the cylinder.

Located between the convolutions of the tooth-strip 11 is another tooth-strip 15, the 80 base 16 of which is not as thick as the base 13 of the tooth strip 11, and when located in the space between the convolutions of the strip 11, the shoulder on the tooth 16 is on the same plane as the shoulder of the strip 85 11, as clearly shown in Fig. 5. The teeth 17 of the strip 15 are short and are substantially of the same shape as the longer teeth 12 of the strip 11, as clearly shown in Fig. 6.

The teeth 17 extend close to the ends of 90 the long teeth of the strip 11, so that any strands which would ordinarily pass longitudinally through the space between the two long teeth would be engaged by the short teeth of one cylinder and the long teeth of 95 the other cylinder, and would be separated into fibrous form by the two sets of teeth.

The two toothed wires of the intersecting rolls are wound in opposite directions, that is, the teeth of the two strips of the stripper 100 are wound left-handed, while the strips on the workers are wound right-handed, each roll making the same number of turns, and consequently the stripper will not interfere,

the longitudinal movement of the several rolls being prevented by the flanges 8 on the gear-wheel 6 mentioned above.

I claim:—

5 1. The combination in a Garnett machine, of two cylinders, each cylinder having two sets of teeth, one set of teeth being of less height than the teeth of the other cylinder, and the teeth of one cylinder extending into 10 the spaces between the long teeth of the other cylinder.

2. The combination in a Garnett machine, of two cylinders, each cylinder having Garnett teeth thereon arranged in spiral form, 15 the teeth of one cylinder being wound as a right-hand spiral, and the teeth of the other cylinder being wound as a left-hand spiral, the teeth of one cylinder extending into 20 spaces between the teeth of the other cylinders; means for driving the two cylinders; and means for keeping the cylinders in longitudinal alignment.

3. The combination of a Garnett cylinder, having a spiral groove therein; a toothed 25 strip located in the groove and forming a spiral whose convolutions are substantially parallel; and a second toothed strip located in the space between the convolutions of the first strip.

30 4. The combination in a Garnett cylinder, having a spiral groove therein; a toothed strip located in the groove and forming a spiral whose convolutions are substantially parallel; and a second toothed strip located 35 on the cylinder in the spaces between the

convolutions of the first strip, the teeth of the second strip being of less height than those of the first strip.

5. The combination of a Garnett cylinder, having a spiral groove therein; a toothed strip, the base of said strip being located in the groove, one side of the strip being at right angles to the base of the groove, the other side being shouldered and having teeth tapered from the shoulder to the point; and a second strip located between the convolutions of the first strip and having a base and tooth formed similar to the first strip, the teeth of the second strip being less in height than those of the second strip. 50

6. The combination in a Garnett machine, of two cylinders, each cylinder having a spiral groove therein, one of said grooves being a right-hand spiral, and the groove of the other cylinder being a left-hand spiral, 55 the convolutions of the grooves being spaced apart a given distance; a toothed strip mounted in the groove of each cylinder, said strip having long teeth; and a second toothed strip located in the spaces between 60 the convolutions of the first strip and resting on the cylinder, the teeth of said second strip being less in height than those of the second teeth, the teeth of the cylinders being arranged so that the long teeth of one 65 cylinder will extend into the peripheral line of the teeth of the other cylinder and in close proximity to the short teeth of the said short cylinder.

THOMAS W. ALLEN.
